BARRETTE

Nathan L. Soiomon, Englewood, N. J.

Application April 18, 1945, Serial No. 588,914

12 Claims. (Cl. 132—48)

1

This invention deals with hair holding means generally known in the art as barrettes. Specifically the invention pertains to that class of barrettes wherein the clasps thereof are fastened to an ornamental support of suitable plastic, such as polymetal, methyl methacrylate, polystyrene, cellulose acetate, or the like. With the prior art barrettes, in the matter of assembly, the clasp was first positioned relative to support and thereafter certain processing of the support was required to hold the clasp fixedly thereto. This required extra time and needless assembly steps, thus enhancing the cost per unit. Moreover, the legs of the clasp in part characterized a loop wherein the legs thereof were substantially of the same length and the proximal leg relative to the support was completely embedded in the plastic body or fastened by flanges requiring subsequent processing. According to the invention and the primary object thereof is to provide a preformed plastic body for a barrette having an appropriately formed and relatively shallow and relatively short channel or opening at one end thereof for conveniently but forcefully receiving a relatively short claw or hooked portion of the clasp adapted to be frictionally and quickly anchored to the walls of the shallow channel without further processing of the plastic support of the companion hook. Other and important objects of the invention will appear from the following detailed specification considered in the light of the accompanying drawings wherein:

Fig. 1 illustrates an inside view of the barrette according to my invention illustrating the clasp removably interlocked with the keeper thereof.

Fig. 2 is a longitudinal sectional view on the line 2—2 of Fig. 1.

Figs. 3 and 4 are transverse sectional views on the line 3—3 and 4—4 of Fig. 1.

Fig. 4A is a view similar to Fig. 4 also illustrating the claw portion of the clasp force fitted to the support.

Fig. 5 is a view similar to Fig. 1 showing another embodiment.

Fig. 6 is a longitudinal sectional view on the line 6—6 of Fig. 5.

Fig. 7 is a transverse sectional view on the line 7—7 of Fig. 5.

Fig. 8 is a fragmentary view of a clasp illustrating the convexed toothed or serrated claw.

Fig. 9 is a fragmentary view of another embodiment illustrating the clasp of Fig. 8 anchored and force fitted thereto.

Fig. 10 is a view on the line 10—10 of Fig. 9.

Fig. 11 is a view similar to Fig. 8 however the 55 frictionally and securely binds against the walls

toothed claw thereof is concaved instead of convexed.

Fig. 12 is a view similar to Fig. 9 but with the clasp of the type shown in Fig. 11 anchored and force fitted to the support.

Fig. 13 shows another embodiment but with the clasp disassociated from the plastic body or support.

Fig. 14 is a transverse sectional view on the 10 line 14—14 of Fig. 13, and

Fig. 15 is a fragmentary perspective view of the clasp shown in Fig. 13.

Illustrative of the several embodiments disclosed, the barrette is generally denoted B having a suitably preformed body or support S of a suitable plastic material of the type hereinbefore mentioned and from which extends the keeper K. Associated with each support is a metal clamp broadly designated as c.

20 In the form according to Figs. 1—4 the clamp c comprises a transversely curved jaw or pin member 10 having a curved end or loop portion 11 integrally merged with a claw 12 forming a hook portion at said end of the pin member. The support S is provided with a relatively shallow dovetailed opening or channel 13 having the tapering sides 14 which closely and frictionally retain the claw or hook 12 in the channel 13 against the bottom wall 15 of the latter. By 25 this action the claw or hook 12, after having been force fitted into the channel, is firmly anchored and frictionally held against slippage or displacement relative to the support or backing S. The pin member or jaw 10 may be desirably shifted or swung to interlock with or disengage from the keeper K. When disengaged, the hair to be clasped may be inserted between the backing and the jaw after which the free end of the latter is 30 swung to interlock with the keeper. The U-shaped or loop portion 11 characterizes a hinge, permitting the jaw to be displaced laterally of the claw 12 and the keeper K.

In Fig. 4A, claw 12a is force fitted into the shallow channel 13a and frictionally binds against the walls thereof, the channel cross sectionally corresponding to the cross section of the claw. In this figure, 10a represents the pin member or jaw and 11a the curved pin portion.

According to the embodiment illustrated in 50 Figs. 5—7 inclusive, the shallow channel or opening 13b although in the support S is in part formed by the closure web 16. As in the case of the form shown in Figs. 1—4 and 4A, when the claw 12b is force fitted into channel 13b, it 55 frictionally and securely binds against the walls

thereof and the binding action of the claw in Figs. 6 and 7 would take place against the parallel surfaces characterizing the channel 13b. In other aspects, the form according to Figs. 5-7 is along the lines of Figs. 1-4 and 4A. In these figures, 10b, 11b and 12b represent like parts of the structure as shown in Figs. 1-4 inclusive.

Concerning the form shown in Figs. 8-10 inclusive, the channel or opening 13c generally decreases in width from the mouth or entrance thereof for stressing the convexedly shaped claw 12c of the jaw 10c after reception. This opening may be said to be tapered by reason of its diverging walls 17 and 18 and the latter slightly depress the convexed or curved jaw after the latter is forcibly driven into the channel 13c. It will be observed that this jaw has its sides provided with the spaced teeth or serrations 19 for cooperating with the rectilinear faces 20 of the flared opening 13c. Therefore as previously stated when this toothed or corrugated claw is inserted into the tapered opening 13c it is slightly deformed or flattened longitudinally, thus placing it under tension and when it strikes the stop face 21, it is appreciably under tension and the teeth 19 grip the parallel walls 20 of channel 13c. By this action, claw 12c is fixedly anchored to the support or backing S. In other aspects the form according to Figs. 8-10 is along the lines of Figs. 1-7. In other words, 11c represents the curved end and 16c the equivalent of the closure web 16 of Fig. 6.

The embodiment according to Figs. 11 and 12 is identical to the form shown in Figs. 8-10 except that the toothed or corrugated claw 12d of the jaw 10d instead of being longitudinally convexed is longitudinally concaved and is desirably deformed and placed under tension when inserted into a tapered opening 13d and the toothed sides 19d grip the side walls of this opening for anchoring purposes. In these figures, 11d represents the curved end and, in Fig. 12, 20d is the same as 20 of Figs. 9 and 10.

In Figs. 13-15, the shallow opening or channel 13e is on a bias relative to the long axis of the backing S and as in the case of the forms shown in Figs. 1-12 force fittingly receives the inclined claw or hook 12e having an enlarged head 22 embodying an aligned pair of teeth 22' and in the matter of assembly, the head 22 is driven into the channel 13e and the teeth thereof frictionally grip the side walls of the channel for permanent anchoring. In other aspects the form shown in Figs. 13-15 are along the lines of the embodiment of Figs. 1-12.

In all of the forms disclosed, the claw or hook of the clasp is frictionally but firmly secured to the plastic body or support and especially to the walls of channel thereof, thus providing a permanent anchorage. By the present arrangement, the channel or opening may be relatively shallow and the length thereof be relatively short. Thus appreciable material may be saved in the matter of forming the clasp. Moreover, by the herein disclosed method of assembly, appreciable time is saved, in that only a short application of force on the loop portion 11 is required for the claws to reach the stop means 21 of Fig. 9, 21' of Fig. 2, 21b of Fig. 6, 21d of Fig. 12 and 21e of Fig. 13, and skilled help is necessary.

Various changes may be made in details of construction and arrangement of parts without departing from the spirit of the invention or sacrificing any of the advantages thereof in-

herent therein. The stops 21, 21', 21b, 21e form closed ends to the respective channels and the channels 13, 13a, 13b, 13c, 13d and 13e all open through the other ends of the channels for free insertion of the claws 12, 12a, 12b, 12c, 12d and 12e. For purposes of description, the channel of Figs. 9-12 may be considered a conical socket for the reception of the claw or mounting end of the pin member or clasp.

10 I claim:

1. In a barrette, a support having an integral hook-shaped keeper on one surface and adjacent one end thereof, said support having a short channel at the other end thereof, the inner end of the channel having a stop wall, the other outer end of the channel being open, an elongated clasp comprising a jaw, a claw integrally joining the jaw in an inwardly curved portion at one end of the jaw, said claw being force fitted within the walls of said channel in retaining the clasp against displacement from said support, and said jaw and keeper having cooperating means for retaining the jaw against displacement from said keeper.
2. In a barrette, a support having an integral hook-shaped keeper on one surface and adjacent one end thereof, said support having a short channel at the other end thereof, the inner end of the channel having a stop wall, the other outer end of the channel being open, an elongated clasp comprising a jaw, a claw integrally joining the jaw in an inwardly curved portion at one end of the jaw, said claw being force fitted within the walls of said channel in retaining the clasp against displacement from said support, said jaw and keeper having cooperating means for retaining the jaw against displacement from said keeper, and the free end of said claw abutting the stop wall in mounting the claw in said channel.
3. In a barrette, a support having an integral hook-shaped keeper on one surface and adjacent one end thereof, said support having a short channel at the other end thereof, the inner end of the channel having a stop wall, the other outer end of the channel being open, an elongated clasp comprising a jaw, a claw integrally joining the jaw in an inwardly curved portion at one end of the jaw, said claw being force fitted within the walls of said channel in retaining the clasp against displacement from said support, said jaw and keeper having cooperating means for retaining the jaw against displacement from said keeper, and said channel being dovetailed in cross-sectional form.
4. In a barrette, a support having an integral hook-shaped keeper on one surface and adjacent one end thereof, said support having a short channel at the other end thereof, the inner end of the channel having a stop wall, the other outer end of the channel being open, an elongated clasp comprising a jaw, a claw integrally joining the jaw in an inwardly curved portion at one end of the jaw, said claw being force fitted within the walls of said channel in retaining the clasp against displacement from said support, said jaw and keeper having cooperating means for retaining the jaw against displacement from said keeper, and said support having a web overlying the claw in said channel.
5. In a barrette, a support having an integral hook-shaped keeper on one surface and adjacent one end thereof, said support having a short channel at the other end thereof, the inner end of the channel having a stop wall, the other outer

end of the channel being open, an elongated clasp comprising a jaw, a claw integrally joining the jaw in an inwardly curved portion at one end of the jaw, said claw being force fitted within the walls of said channel in retaining the clasp against displacement from said support, said jaw and keeper having cooperating means for retaining the jaw against displacement from said keeper, said support having a web overlying the claw in said channel, and said claw having teeth engaging walls of said channel.

6. In a barrette, a support having an integral hook-shaped keeper on one surface and adjacent one end thereof, said support having a short channel at the other end thereof, the inner end of the channel having a stop wall, the other outer end of the channel being open, an elongated clasp comprising a jaw, a claw integrally joining the jaw in an inwardly curved portion at one end of the jaw, said claw being force fitted within the walls of said channel in retaining the clasp against displacement from said support, said jaw and keeper having cooperating means for retaining the jaw against displacement from said keeper, said support having a web overlying the claw in said channel, and said claw having curved in longitudinal form.

7. In a barrette, a support having an integral hook-shaped keeper on one surface and adjacent one end thereof, said support having a short channel at the other end thereof, the inner end of the channel having a stop wall, the other outer end of the channel being open, an elongated clasp comprising a jaw, a claw integrally joining the jaw in an inwardly curved portion at one end of the jaw, said claw being force fitted within the walls of said channel in retaining the clasp against displacement from said support, said jaw and keeper having cooperating means for retaining the jaw against displacement from said keeper, said support having a web overlying the claw in said channel, said claw being curved in longitudinal form, and side edges of the claw having projecting teeth.

8. In a barrette, a support having a hook-shaped keeper on one surface and adjacent one end thereof, said support having a short channel at the other end thereof, said channel being defined by top, bottom, side and one end wall, the other end of the channel being open, the top and bottom walls of the channel being flared one with respect to the other in the direction of the open end of the channel, an elongated clasp comprising a jaw, a claw integrally joining the jaw in an inwardly curved portion at one end of said jaw, said claw having arcuate formation for frictional engagement with the walls of said channel in force-fitting the claw in said channel to retain the clasp against displacement from said support, and the free end portion of the jaw of said clasp engaging the keeper in retaining said clasp against accidental displacement therefrom.

9. In a barrette, a support having a hook-shaped keeper on one surface and adjacent one end thereof, said support having a short channel

at the other end thereof, said channel being defined by top, bottom, side and one end wall, the other end of the channel being open, the top and bottom walls of the channel being flared one with respect to the other in the direction of the open end of the channel, an elongated clasp comprising a jaw, a claw integrally joining the jaw in an inwardly curved portion at one end of said jaw, said claw having arcuate formation for frictional engagement with the walls of said channel in force-fitting the claw in said channel to retain the clasp against displacement from said support, the free end portion of the jaw of said clasp engaging the keeper in retaining said clasp against accidental displacement therefrom, and said claw having teeth adapted to engage the walls of said channel.

10. In devices of the class described comprising a supporting body having a socket, said body adjacent one end thereof, an elongated pin member, a mounting end portion joining one end of the pin member in an integral curved portion offsetting the mounting end with respect to the pin member, the cross-sectional area of said socket being greater than the cross-sectional area of said mounting end, said mounting end being curved for frictional engagement with the socket walls in force-fitting of the mounting end in said socket, and means checking inward movement of the mounting end in said socket.

11. A clasp for barrettes having a clasp mounting socket at one end thereof, said clasp comprising an elongated pin member, a mounting claw at one end of the pin member, said claw joining the pin member in an integral curved portion spacing the claw from said pin member, the cross-sectional area of the socket being greater than the cross-sectional area of the claw, and the claw of said pin member being longitudinally curved.

12. A clasp for barrettes having a clasp mounting socket at one end thereof, said clasp comprising an elongated pin member, a mounting claw at one end of the pin member, said claw joining the pin member in an integral curved portion spacing the claw from said pin member, the cross-sectional area of the socket being greater than the cross-sectional area of the claw, the claw of said pin member being longitudinally curved, and side edges of the claw having projecting teeth.
